UNITED STATES PATENT OFFICE.

JOHAN BORE AND ALBERT SKOGLUND, OF GOTTERBORG, SWEDEN, ASSIGNEES TO
CARL AXEL ARVID WESTERBERG, OF STOCKHOLM, SWEDEN.

STEAM CLEANSING DEVICE FOR LOCOMOTIVE BOILERS OR THE LIKE.

Application filed January 20, 1919. Serial No. 272,076.

To all whom it may concern:

Be it known that we, JOHAN BORE and ALBERT SKOGLUND, subjects of the King of Sweden, residing at Gottenborg, Sweden, 5 have invented certain new and useful Improvement in Steam Cleansing Devices for Locomotive Boilers or the like, of which the following is a specification.

In marine boilers and sometimes also in 10 stationary boilers the use of steam cleansing or sweeping devices is well known for the cleansing of the tubes, the said devices primarily consisting of a steam supply pipe with a discharge nozzle the latter being entered into the fire box or into the smoke uptake in such a position that the escaping steam may act upon the tubes, either in the direction of the draft, or contrary to such direction. In locomotive boilers where an 15 inclined bridge is generally disposed in front of part of the set of tubes the employment of such an apparatus is rendered difficult on account of the excessive heat preventing the apparatus from being entered 20 into the furnace so far as to keep the steam jet from being obstructed by the bridge. As it is hardly possible for a person to work in front of the boiler when driving the locomotive, the cleansing or sweeping apparatus cannot be brought into the smoke box from the 25 front end of the locomotive. The above circumstances, therefore, always necessitated the sweeping of locomotives to take place at intervals when the engine was not in active 30 operation, this naturally involving a considerable loss of time, besides which the draft of the locomotive is reduced, particularly when driving over long distances, through the masses of grime which in the meantime 35 gather in the comparatively narrow and long tubes.

The present invention relates to a contrivance by means of which the said difficulties are overcome so that sweeping may take 40 place at any time during the run of the engine.

The invention is principally characterized by this that a steam supply pipe provided with a discharge nozzle is fitted in the furnace in such way as to enable the nozzle to be brought into the furnace in known manner, also during the run of the locomotive, as might be required, and placed in such a position by means of manœuvring devices accessible in the driver's cabin, that the es-

caping steam will hit the tubes and enter the same, the said discharge nozzle being also adapted to be brought out of the furnace so far that it is withdrawn from direct contact with the furnace gases.

An embodiment of the invention is shown in the accompanying drawings, in which Fig. 1 shows a vertical longitudinal section of part of the locomotive boiler. Fig. 2 is a vertical cross section of the same part, and Figs. 3 and 4 respectively represent a horizontal section and an elevation of the part of the boiler shown in Figs. 1 and 2. Figs. 5 and 6, which are drawn to a larger scale, show two horizontal sections of a smaller part of the same boiler fitted with a steam sweeping device, and Fig. 7 is a plan view of the details according to Fig. 6, some of the parts being shown in section.

1 designates the shell plate of the locomotive boiler, the furnace 2 being arranged within it in known manner. The furnace 2 is connected with the smoke box by means of an upper group of larger tubes 3 and a lower group of smaller tubes 4. An inclined bridge 5 in known manner prevents the fire from entering the tubes 3, 4 directly. At the one side of the furnace 2 a steam supply pipe 6 is inserted through a pipe 7 passing through the water room between the walls 1 and 2, the said pipe 7 being fitted water tight to the plates 1 and 2. The steam supply pipe 6 is rotatably and slidably mounted in a casing 16 secured to the plate 1, the said casing being provided with a chamber 25 supplied with steam from the boiler through a pipe 9. The chamber 25 communicates with the inner side of the pipe 6 through apertures 26 in the latter when the pipe 6 occupies the position shown in Fig. 6. At the end adjacent to the furnace the steam supply pipe 6 is fitted with a discharge nozzle 11 provided with a blow-through-channel 12 which, in known way is shaped so as to give the escaping steam a flattened out fan-like spreading. The pipe is provided with a manœuvring contrivance 8 reaching into the driver's cabin 10. The said manœuvring contrivance according to the embodiment shown partly consists of a lever 18 engaging a pin 15 with its forked end, the pin 15 passing through the part of the pipe 6 which is outside of the casing 16. The free end 21 of the pin 15 is provided with a slot, this slot

being entered by a stud 27 on an arm 20. The arm 20 is secured to a rod 19 which is mounted on the rod 13 by means of screws 23 so that the rod 19 and the rod 13 together form a part of the manœuvring contrivance 8. The screws 23 are adapted to pass through slots 24 provided in the rod 19, so that the latter may be moved relatively to the rod 13. The rod 19 is extended 10 through the wall 10 and turned to a handle 22 on the inside of the said wall 10.

The operation of the apparatus is as follows:

When sweeping is to be done, the steam supply pipe 6 is entered into the furnace by means of the rod 19, this rod being adapted to swing in the manner of a lever fulcrumed in the wall of the driver's cabin. This being done, the apertures 26 of the pipe 6 are brought within the chamber 25 on the casing 16 communicating with the pipe 9 so as to cause the steam to be discharged through the channel 12 of the nozzle 11 against the tubes, as is diagrammatically shown by full lines in Fig. 1. Through the manipulation of the handle 22 the pin 15, 21 and the pipe 6 may be turned from within the driver's cabin by sliding the rod 19, 20 to and fro so that the steam jet will sweep over all of the tubes 3 and 4 in turn, or only over part of them, as may be desired. The sweeping having been done, the pipe 6 is drawn in so far within the pipe 7, by swinging of the rod 13, that the edge 17 of a cap enclosing the nozzle 11 will abut against a sleeve 18 projecting from the casing 16 into the pipe 7. By this withdrawal of the pipe 6 with its discharge nozzle 11 these parts are protected against any damage from the fire and the 40 hot gases in the furnace. Through the withdrawal of the pipe 6 within the pipe 7 the steam apertures 26 will be moved out of range of the chamber 25 (see Fig. 5) and the supply of steam is hereby discontinued 45 without a separate shut-off valve having to be manipulated.

By means of the manœuvring contrivance 8 formed by the rods 13 and 19 the whole apparatus may be easily and conveniently 50 operated, and all of the tubes, or only a part thereof, may be swept over by the steam jet by turning the apparatus through an angle less than 180°.

The device shown in the drawings and described hereinbefore evidently only represents an embodiment of the invention which may be modified in its details without departing from the spirit or the scope of the invention. Thus, for instance, the apparatus 55 may be disposed vertically or it may be entered obliquely through the top of the furnace instead of being inserted from the side thereof; the discharge nozzle may be differently shaped, and the manipulation of the apparatus may be effected otherwise and

by other means than hereinbefore described, provided the characteristic feature of the apparatus is such, that it may, when acted upon from within the driver's cabin, also during the run of the locomotive, send the 70 steam jet against the whole of the set of tubes, or only against a part thereof, so as to force the grime out of the tubes.

Claims.

1. A locomotive boiler, having a cab at 75 its rear end, a furnace having a side wall, a set of boiler tubes extending lengthwise from the furnace, a tubular nipple extended through the wall with its axis extending across the axes of the tubes and a steam discharge pipe slidably and rotatably arranged within the nipple, said pipe having a nozzle, and means operable from the cab for turning the nozzle and sliding it transversely of the axis of the tubes for directing the steam 80 into all of said tubes from said nozzle.

2. A locomotive having a cab, a furnace with a side wall, and boiler tubes leading from the furnace, a tubular nipple with its axis arranged transversely of the axes of 90 the tubes and extending through the side wall; a steam discharge pipe having a hole through its wall, said pipe being slidably and rotatably arranged within the nipple, said nipple having therein a steam chamber, 95 a steam pipe leading to said chamber, and means extending to the cab whereby said first mentioned pipe may be moved by a person in the cab lengthwise to bring the hole in the pipe into communication with the 100 steam chamber and the pipe oscillated as described.

3. In a steam boiler, a cab, a furnace having a side wall, a battery of tubes, a tubular nipple in said wall and a steam discharge 105 pipe rotatably arranged within the nipple and slidably therein in directions transverse of the tubes axes, said pipe having a nozzle flared to effect a spreading of the steam jet in the shape of a fan, part of the jet being 110 directed at right angles to the axis of the discharge pipe and part at acute angles thereto, means for operating the pipe extending to the cab whereby, by small lengthwise and oscillating movement of the nozzle, 115 115 a person in the cab, steam may be projected into the ends of all said tubes.

4. A locomotive boiler having a cab, a furnace with a side water wall tubes leading from the furnace, a tubular nipple with its axis arranged transversely through the said side water wall at a point beyond the terminals of the tubes and outside the extension of all of said tubes, a steam discharge pipe slidably and rotatably mounted within the nipple, a nozzle on the end of the discharge pipe flared to effect a fan-like spreading of cleaning steam, and means operable from the cab for effecting the sliding and rotating of the 120 discharge pipe.

5. In a locomotive of the character described, the combination with a boiler having side water walls, a furnace within the boiler and provided with a fire bridge and a plurality of tubes leading from the furnace, of a tubular nipple arranged transversely through one of the side water walls at a point between the terminals of the tubes and said bridge, said point being so located that the steam jet issuing from said nozzle may be directed to blow into all the tubes without hindrance of the upper edge of the fire bridge, a steam discharge pipe slidably and rotatably arranged through said nipple, a nozzle on the end of the discharge pipe flared for effecting a fan-like spreading of the exhausting steam and means within the cab of the locomotive for effecting the sliding and rotating of the discharge pipe.
- 10 6. In an apparatus of the character described, the combination with a locomotive boiler having side water walls, a furnace within the boiler and tubes leading from the furnace, of a tubular nipple arranged transversely through one of the said side water walls at a point beyond the terminals of the tubes and outside the extension of all said tubes, a steam discharge pipe slidably and rotatably mounted within the nipple, a nozzle on the end of the discharge pipe flared to effect a fan-like spreading of exhausting steam, and means connected with the opposite end of the discharge pipe and leading into the driver's cab for sliding and rotating the discharge pipe.
- 15 7. An apparatus of the character described including in combination, a boiler, a furnace therein, boiler tubes leading from the furnace, a pipe arranged through the walls of the furnace and boiler having its axis at right angles to the longitudinal axes of the tubes, a casing in the pipe, a discharge pipe slidably and rotatably arranged through the casing and the first mentioned pipe and co-acting with the casing to form a valve for controlling the passage of steam into the furnace, a nozzle on the inner end of the discharge pipe, and means for sliding and rotating the discharge pipe.
- 20 8. An apparatus of the character described including in combination, a boiler, a furnace arranged therein, pipes leading from the furnace, a bridge in the furnace, a pipe arranged through the walls of the furnace and boiler positioned above the bridge and having its axis at approximately right angles to the longitudinal axes of the pipes, a casing in the pipe, a discharge pipe slidably and rotatably arranged through the casing and co-acting with the casing to form a valve for controlling the passage of steam into the furnace, a nozzle on the inner end of the discharge pipe, and means arranged within convenient reach of the operator or driver for manipulating the pipe.
- 25 9. In testimony whereof we affix our signatures in presence of two witnesses.
